UNITED STATES PATENT OFFICE.

THOMAS A. MARTIN, OF COVINGTON, KENTUCKY, ASSIGNOR OF ONE-HALF TO FRED J. WARNER, OF MEMPHIS, TENNESSEE; MARY MARTIN ADMINISTRATRIX OF SAID THOMAS A. MARTIN, DECEASED.

TOY.

No. 897,638.

Specification of Letters Patent.

Patented Sept. 1, 1908.

Application filed June 6, 1907. Serial No. 377,619.

To all whom it may concern:

Be it known that I, THOMAS A. MARTIN, a citizen of the United States, residing at Covington, in the county of Kenton and State of Kentucky, have invented certain new and useful Improvements in Toys, of which the following is a specification.

My invention relates to whirligig toys, and has for its object the providing of a toy of this character comprising a transversely grooved stem having a revoluble part loosely pivoted at its end in such manner as to cause revolving of the revoluble part upon rubbing the transversely grooved stem longitudinally of the stem with a suitable rubber, which may also be arranged to contact either side of the stem for causing the rotation of the revoluble part to take place in either direction, and the invention will be readily understood from the following description and claims, and from the drawing, in which latter:

Figure 1 is a perspective view of my improved device as seen from the handle end, with the rubber pushed against one side of the stem. Fig. 2 is a perspective view of my improved device as seen from the revoluble-part end, with the rubber pushed against the other side of the stem. Fig. 3 is a side elevation of the stem with its revoluble-part pivoted thereto, and with the rubber in position. Fig. 4 is an end elevation, viewed from the revoluble-part end, with the head of the securing pin omitted for showing a preferred relative proportion between the size of the pivotal aperture in the revoluble-part and the pivotal pin; and, Fig. 5 is a cross-section on the line x-x of Fig. 3.

1 represents a stem which is provided with suitable notches 2, preferably at the upper and lower edges of the stem. The stem may be of wood or other suitable material. I prefer that this stem shall be substantially rectangular in cross-section, with the notches provided at either one or both of the upper and lower corners of the rectangle. At one end of the stem a revoluble-part 3 is pivoted on a pin 4 preferably having a large head. 5. This revoluble part may be of any suitable shape or size and is preferably of cardboard, although other materials may be employed, but I desire that the same shall be

light. In order to give the revoluble part freedom of motion upon the pin, I provide 55 it with an aperture 6 sufficiently larger than the pin to permit the revoluble-part to turn very freely, and preferably providing substantial play between the revoluble-part and pin, and in order to aid this further, I also 60 prefer to provide suitable space 7 between the end of the stem and the head of the pin. The stem also has a handle 8.

9 is a rubber which may be of wood or other suitable material and is preferably in 65 the form of a blade provided with a notch 10 in the edge thereof preferably wider than the width of the stem and having side contact-surfaces 11 12 and at the bottom of the notch having a rubbing-face 13. 70

When now the stem is held in one hand by the handle 8 and the rubber is moved forwardly and backwardly over the notches of the stem more or less rapidly, the stem will be subjected to vibrations. The more rapidly the rubber is rubbed along the stem the more frequent will these vibrations be. These vibrations will be communicated to the revoluble-part. If the rubber is rubbed upon the stem with its side contact-face 11 80 against one side of the stem, for instance, the side 14, which forms a side rubbing-face, the revoluble-part will be caused to revolve with its upper edge toward the left, looking in the direction shown in Fig. 1. If however the 85 rubber is rubbed along the stem with its other side edge 12 of the notch 10 against the other side 15 of the stem, which also forms a side rubbing-face, the revoluble-part will be caused to revolve in the opposite direction, 90 or toward the right, viewed in the direction shown in Fig. 1. The latter position of the rubber is indicated in Fig. 2. The transference of contact from one to the other of said side-faces is accomplished without removing the rubber from contact with the notched surface. If desired the transverse notches in the stem may be extended a further distance around the stem or completely surround the stem, as may be desired, and 100 the stem may also be of different cross-section.

Having thus fully described my invention what I claim as new and desire to secure by Letters Patent is:

A device for operating whirligig toys by

rubbing the stem thereof consisting of a blade having a notch in the edge thereof, wider than the whirligig stem and providing by its bottom a rubbing-face and by its 5 ends two contact-faces, substantially as described.

In testimony whereof I have subscribed

my name hereto in the presence of two sub-
scribing witnesses.

THOMAS A. MARTIN.
